PIPE-CLEANING SNAKE AND OPERATING
HANDLE THEREFOR

Frank E. Flinn, Miami, Fla.

Application January 20, 1947, Serial No. 723,125

4 Claims. (Cl. 15—104.30)

1

This invention relates to novel forms of probing rods or snakes used by plumbers, electricians, telegraph and telephone linemen, and others for passing through pipes or tubes to clear them of obstructions, loosen congested matter therein, or to guide a flexible wire or line therethrough.

The use of snakes has often been accompanied by extreme difficulty in pushing or pulling them through the pipe or tube because of excessive friction and poor gripping means. Gripping with the handle would provide very little gripping pressure, causing the hands to burn from friction or slipping over the snake. When gripping the snake with pliers, the snake would often bend and become kinked making it useless for the purpose it was intended.

The object of the present invention is not only to eliminate the above difficulties, but further to provide simultaneously means for indicating the distance between various points in the pipe or tube in which the novel snake is used, by providing the snake strip with a series of beads equally spaced at known intervals and having a simple, easily detachable gripping means for cooperation with the beaded portions of the snake to prevent slipping and reduce the tendency to bend or kink the snake.

A further object is to make a novel form of snake and gripping means therefor, which are simple but effective to reduce friction in the pipe or tube, as well as provide measuring means to indicate the distance to an obstruction, or the length of the pipe or tube, and to prevent slipping of the gripping means.

A further object is to provide a non-slipping gripping block for a beaded snake having a slot for said snake and a socket at one end in the bottom of said slot for a bead to enter and lock the block against slipping along said snake.

A further object is to construct a gripping block for a snake strip having beads formed at intervals thereon, which will readily slip over an unbeaded portion and stop on said bead to form a non-slipping grip whereby to push said snake axially with little tendency to bend or kink it.

Other and more specific objects of the present invention will appear in the following detailed description of one form of device constructed in accordance with the invention, having reference to the accompanying drawing, wherein:

Figure 1 shows a portion of a snake strip, broken between the successive beads to shorten the figure, with a gripping block mounted in place for pushing or pulling the snake upwardly,

2

Figure 2 shows a portion of the same snake strip and gripping block turned through 90° about the axis of the snake from the position shown in Figure 1.

5 Figure 3 is a view of the block by itself in the same position as shown in the combination of Figure 1.

Figure 4 is a view of the block turned through 90°.

10 Figure 5 is an end view of the block as seen from above in Figures 1, 2, or 3.

Figures 6 and 7 are sectional views of the block taken on the lines 6—6 of Figure 4 and 7—7 of Figure 3, respectively, and

15 Figure 8 is a sectional view of a bent end portion of a pipe with the corresponding portion of a snake being pushed therethrough, and a gripping block placed thereon for pushing the snake.

20 Figure 9 is a cross-sectional view of a preferred form of snake body portion.

25 Referring now to the drawings, the snake 1 has its body portion of non-circular contour, preferably being oblong in cross-section with parallel side faces—and has beads 2 formed thereon at intervals which may be of a predetermined length, adaptable for insertion in a pipe or tube for the purposes outlined above.

30 The gripping block 3 may be made of metal or other suitable material and is large enough to provide a good grip by hand. It has a slot 4 extending from one of its narrower sides 5 to approximately its middle. Here, one end of the slot is enlarged to allow a bead to freely pass through this end, the rest of the slot being just big enough to allow an unbeaded portion of the snake strip to slip through it edgewise. This enlarged portion of the slot is shown at 6 and extends approximately to the center of the block.

35 With such construction, it will be readily seen, as shown in Figure 8, that the snake when passed through a pipe or tube will touch the sides of said pipe or tube only at the bead points, thus reducing the friction which an ordinary snake strip without the beads would normally produce. 40 This means a considerable reduction of effort required to push or pull a snake through any particular pipe or tube.

45 In Figure 8, the snake 1 is being pushed through the pipe 7 by means of the block 3, which has been slipped onto the strip above the bead 2', with the enlarged end portion of the slot 6 extending downwardly, and then moved down so that bead 2' entered said enlarged portion and was stopped by the upper end thereof where it narrows to the thickness of the snake strip. Thus,

the block will not slip off the strip, nor any further along the strip when pushed forwardly.

When the snake is pushed down by means of the gripping block as far as possible, the block is backed off the bead by moving it upwardly along the snake strip and then slipped off the strip. A new hold is established at another bead higher up on the snake strip in the same manner, and the snake is pushed further into the pipe, etc.

If it were desired to pull the snake out of pipe 1, the block 3 would be reversed so that the enlarged portion 6 would extend upwardly and the block would be slipped onto the strip below one of the beads and then moved upwardly over the bead to provide a non-slip contact therewith in reverse direction. The advantages of the assembly of the snake and its operator are more or less obvious. Since the snake body is oblong in cross-section, and the width of the operator kerf 4 is greater than the thickness of the snake body but less than the width of such body, the two can be assembled only by positioning the operator between successive snake beads and providing relative movement of operator and snake edgewise of the snake to place the snake in the axial zone of the operator. Since the kerf enlargement is limited to the axial zone of the operator and extends from an intermediate point in the zone length to an end of the operator, the remainder of the kerf in the axial zone maintains the kerf width condition which prevents rotation of the snake within the operator. Hence, any positioning of the operator on the snake—whether in position relative to a bead point or between adjacent bead points—so connects the operator and snake that any movement of the operator rotatively will provide a corresponding movement of the snake.

The operator must be initially positioned by application to the snake between adjacent beads—a beaded zone cannot enter the kerf through the open side—and then be shifted longitudinally of the snake body to place the bead zone within the operator; this can be done only when the snake body has been moved to the bottom of the kerf—the axial zone of the operator which carries the enlarged portion indicated at 6 which extends from an end of the operator to an intermediate point. When the operator has been moved lengthwise in this zone sufficient to bring the bead into contact with the bottom of the enlargement 6, the assembly is in such condition that not only can the snake be rotated by rotating the operator, but can be advanced—by pushing on the trailing end of the operator—or be moved backward—by drawing the operator in the direction of its leading end. Hence, the operator can be used, at will, for movement of the snake in either direction and at the same time enable the rotative movement of the snake to be had whenever the operator is applied.

As is apparent, the assembly is designed for service more particularly under conditions where it can be readily manipulated by hand operation of the operator, although not limited to such conditions since the operator is of such shape and dimensions as will enable the application of a wrench thereto to aid in providing rotating movement. The operator is fairly small and readily received within the hand or fingers for manipulation in positioning and in service; the snake body cross-section is generally approximately 0.125" in width and 0.0625" in thickness,

thus providing a snake completely serviceable under these conditions.

In this connection, the presence of the bead zones at regular distances and comparatively short distances—a foot, for example—is of definite advantage, due to the fact that the user may employ the operator close to the entrance of the drain on which he is operating, if desired. With the beads spaced a foot apart, the advance is by steps of approximately such length with the operator shifted between steps. Hence, the length of snake exposed between the drain and the operator is comparatively short and thus less likely to bend materially or buckle under turning or pushing pressures. Due to this manner of using the assembly, it is apparent that both snake and operator, while separable, are specifically dimensioned for service in combination, since, in service, the two elements are completely and directly complementary, with both required for the desired efficient service.

The construction is very simple, the device is easily made, and its operation is quick and positive, eliminating slipping of the gripping means and reducing any tendency to bend or kink the snake. Also, if the beads are formed at equal intervals of a foot, a yard, or any other predetermined distance, a count of the number of beads between points in the pipe or tube will indicate the distance advanced, so that the beads not only serve as a means for reducing the friction between the snake and the pipe or tube, but also provide means for indicating distances in the pipe or tube.

Obviously modifications in the form and arrangement of parts of this device may be made without departing from the spirit and scope of this invention, as defined in the appended claims.

What is claimed as new, is:

40. 1. A separable snake and operator assemblage comprising a metallic snake having its cross-sectional body portion non-circular in contour with parallel side faces and having a succession of spaced surface beads, and an operator therefor kerfed longitudinally from its axial zone outward with the kerf width greater than the thickness of the snake body and less than the width of such body, said operator having the kerf enlarged within the axial zone of the operator with the enlargement extending from an intermediate point of such zone length to an end of the operator with the enlargement dimensioned to receive a bead zone of the snake, whereby the operator is positionable on the snake solely when being applied to the snake body intermediate successive bead zones and by relative movement of the snake body edgewise into the kerf depth to such axial zone and then advancing the operator lengthwise of the snake body to position a bead zone within the kerf and in contact with the bottom of the enlargement.

2. An assemblage as in claim 1 characterized in that the snake is formed of a strip of flexible material having a stiffness suitable for pushing through a congested pipe or tube, the body of the strip being oblong in cross-section, said strip carrying a plurality of beaded zones in spaced relation in the direction of length of the strip and with the spacing of predetermined length.

3. An assemblage as in claim 1 characterized in that the operator is of rectangular block contour with the kerf extending from an edge of the block and parallel with the planes of the opposite sides of the block.

4. A snake and operator assemblage comprising

ing a metallic snake, and an operator therefor, said snake having its body of oblong rectangular cross-section with planar sides with the width of a side of greater dimension than the dimension of its thickness, said body having a succession of side beads spaced apart in the direction of length of the snake, said operator having a shaped contour approximately presenting an enlarged simulation of the cross-sectional form of the snake body and having a length materially less than the distance between successive beads of the snake, said operator having its body kerfed longitudinally from its longitudinal axis outward to an edge face of the contour with the kerf width less than the width of the snake body and greater than the thickness of such snake body, said operator additionally having the kerf enlarged in such axial zone to a sectional shape larger in area than the section of said body and limited to such zone with the enlargement extending from an end of the operator to an intermediate point in the length of the axial zone of the operator, whereby the operator is positionable on the snake solely by applying the operator to the snake body between adjacent beads and by relative movement of the body edgewise into the kerf depth to such axial zone and then advancing the operator lengthwise to position a bead zone within the

enlarged portion of the kerf and into contact with the bottom of such enlargement, the positioned operator being cooperative with the snake to provide rotation of the snake body by rotary movement of the operator in any applied position of the operator and with the operator operative to provide advancement or withdrawal of the snake lengthwise of the latter by pushing or pulling pressures applied upon the operator in directions lengthwise of the snake body when a bead zone is seated on the bottom of the enlarged axial zone.
